CLAIM

The ornamental design for a foot switch for a medical device, as shown and described.

DESCRIPTION

FIG. 1 is a top perspective view of the claimed design illustrated in an environment;

FIG. 2 is a top perspective view of the claimed design;

FIG. 3 is a bottom perspective view of the claimed design;

FIG. 4 is a front view of the claimed design;

FIG. 5 is a back view of the claimed design;

FIG. 6 is a right side view of the claimed design;

FIG. 7 is a left side view of the claimed design;

FIG. 8 is a top view of the claimed design; and,

FIG. 9 is a bottom view of the claimed design.

The figures illustrate a foot switch for a medical device. Features of the article that are not shown are disclaimed. Additionally, any features shown in broken lines are for illustrative purposes only and form no part of the claimed design.
